BOX OR CONTAINER

Helen M. Hanson, Argyle, Wis., assignor to
Kalamazoo Vegetable Parchment Company,
Kalamazoo, Mich.

Application May 3, 1933, Serial No. 689,123

7 Claims. (Cl. 229—41)

The main objects of this invention are:

First, to provide a collapsible box which is well adapted for use as a lunch box.

Second, to provide a collapsible box which when erected is rigid and secure, may be easily erected or collapsed, and may be very compactly collapsed.

Third, to provide a box embodying these features which is very economical to produce.

10 Objects relating to details and economies of my invention will appear from the description to follow. The invention is defined and pointed out in the claims.

15 A structure which is a preferred embodiment of my invention is illustrated in the accompanying drawings, in which:

Fig. 1 is a perspective view of my improved box, set up.

Fig. 2 is a perspective view with the cover open.

20 Fig. 3 is a perspective view of the box partially collapsed and illustrating the steps in collapsing or erecting.

Fig. 4 is a perspective view of the box completely collapsed and with a rubber band about it.

25 Fig. 5 is a vertical transverse section on line 5—5 of Fig. 1 with the removable container or holder in position.

Fig. 6 is a perspective view of the removable container or holder.

30 Fig. 7 is a plan view of the blank from which the box is formed.

As most clearly shown in Fig. 7, my improved box is formed of an integral blank of boxboard or other suitable material suitably scored to facilitate

35 folding and provide a bottom 1, front wall 2, rear wall 3 and cover 4, these parts being arranged centrally and in alignment.

The bottom has end walls 5 extending from its ends. These end walls have rear wall flaps 6 and 7 extending from the rear edges thereof and front wall sealing flaps 8 extending from the front edges thereof. These sealing flaps 8 are arranged on the inside of the front wall 2 and fixedly secured thereto as by gluing.

40 The rear wall flaps 6 and 7 have interlocking tongues 9 and 10 respectively on their outer ends, these tongues being detachably engaged and when engaged forming an outer rear wall 45 of the box, as shown in Fig. 2.

The end walls 5 have scores 11 extending from the front lower corners thereof to the upper rear corners; that is, these end walls are diagonally scored from corner to corner permitting 50 the collapsing of the end walls, and the front

wall with the sealing flaps 8 secured thereto upon the bottom, as shown in Fig. 3.

When thus collapsed, the rear wall flaps 6 and 7 collapse upon the rear wall 3, as shown in Fig. 5, with the tongues 9 and 10 overlapping the cover, scores 12 being provided at the base of the tongues to register with the score line joining the cover with the rear wall, these scoring lines between the walls and cover parts being indicated conventionally at 13.

10 The cover has a front flange extension 14 on its outer side edge and end flange extensions 15 on its ends. These end flange extensions have sealing flaps 16 on their outer ends which are lapped on the inside of and secured to the flange 15 extension 14 by glue or other means for permanently and fixedly securing these parts.

Score lines 17 are provided extending from the score line 13 of the front cover flange to the outer edges of the flange extensions 15 so that the 20 end cover flanges and the front cover flange may be collapsed inwardly, as shown in Fig. 3.

With the parts thus arranged, the box may be quickly set up, it only being necessary to unfold from collapsed position, swing up the front and 25 end walls of the box and engage the rear wall flaps or extensions 6 and 7. The cover may then be swung up to closed position, the rear wall 3 lying at the outside of these detachably connected cover flaps 6 and 7 and supporting and covering their 30 connecting parts. The cover flanges are swung outwardly to telescope with the box. When erected, the box is quite rigid and is very secure.

A string or rubber band may be placed around the box to keep the cover in closed position. It 35 cannot collapse until the cover is swung open and the rear wall flaps disengaged.

I preferably provide a collapsible holder or container 18 which is rectangular in cross section and scored at its corners 19 so that it may 40 be flatly collapsed. One wall, as 20, of this holder or container is provided with a tongue 21 adapted to engage in a slit 22 provided therefor in the rear wall extension or flap 7. This provides a suitable holder—one well adapted to receive soft 45 material wrapped in paraffin paper or the like. This holder or container 18 is also formed of boxboard or other suitable material and may be readily collapsed.

My improved box or container is especially designed by me as a lunch box, although well adapted for various uses where collapsible boxes or containers are desired.

50 The structure is very economical to produce, and at the same time may be used repeatedly if 55

desired. It is well adapted to receive advertising matter or may be printed or ornamented as desired without adding considerably to the cost. It is obvious that the box may be varied in size and dimensions according to the use to which it is to be put.

Having thus described my invention, what I claim as new and desire to secure by Letters Patent, is:

- 10 1. A collapsible box formed of an integral blank scored for folding and comprising a bottom, front and rear walls, and a cover disposed in alignment, the cover being joined to the upper edge of the rear wall and having cover flap extensions on its front and end edges, the end extensions having sealing flaps on their front ends lapped upon and fixedly secured to the inner side of the front cover flange, the end cover flanges being scored diagonally from the bases of the front cover flanges to the outer edges facilitating collapsing of the cover flanges inwardly upon the cover, the bottom having substantially square end walls extending from the ends thereof, the end walls having rear wall flaps extending from their rear edges and front wall flaps extending from their front edges, the said rear wall flaps having disengageable interlocking tongues the bases of which are in line with the joint between the cover and the rear wall when the blank is in the flat, the front wall flaps being fixedly secured to the inner side of said front wall, the end walls being diagonally scored from their bottom front corners to their top rear corners to permit collapsing of the front and end walls upon the bottom with the rear wall flaps in overlapping relation to the rear wall, there being scores at the bases of the locking tongues of the rear wall flaps permitting their disposition in overlapping relation to the cover and the collapsing of the cover on the rear wall and the rear wall flaps superimposed thereon.
- 15 2. A collapsible box formed of an integral blank scored for folding and comprising a bottom, front and rear walls, and a cover disposed in alignment, the cover being joined to the upper edge of the rear wall and having cover flap extensions on its front and end edges, the end extensions having sealing flaps on their front ends lapped upon and fixedly secured to the inner side of the front cover flange, the end cover flanges being scored diagonally from the bases of the front cover flanges to the outer edges facilitating collapsing of the cover flanges inwardly upon the cover, the bottom having substantially square end walls extending from the ends thereof, the end walls having rear wall flaps extending from their rear edges and front wall flaps extending from their front edges, the said rear wall flaps having disengageable interlocking parts, the front wall flaps being fixedly secured to the inner side of said front wall, the end walls being diagonally scored from their bottom front corners to their top rear corners to permit collapsing of the front and end walls upon the bottom with the rear wall flaps in overlapping relation to the rear wall.
- 20 3. A collapsible box formed of an integral blank scored for folding and comprising a bottom, front and rear walls, and a cover disposed in alignment, the cover being joined to the upper edge of the rear wall and having cover flap extensions on its front and end edges, the end extensions having sealing flaps on their front ends lapped upon and fixedly secured to the inner side of the front cover flange, the end cover flanges being scored diagonally from the bases of the front cover flanges to the outer edges facilitating collapsing of the cover flanges inwardly upon the cover, the bottom having substantially square end walls extending from the ends thereof, the end walls having rear wall flaps extending from their rear edges and front wall flaps extending from their front edges, the said rear wall flaps having disengageable interlocking parts, the front wall flaps being fixedly secured to said front wall, the end walls being diagonally scored from their bottom front corners to their top rear corners to permit collapsing of the front and end walls upon the bottom with the rear wall flaps in overlapping relation to the rear wall.
- 25 4. A collapsible box formed of an integral blank scored for folding and comprising a bottom, front and rear walls, and a cover disposed in alignment, the cover being joined to the upper edge of the rear wall, the bottom having substantially square end walls extending from the ends thereof, the end walls having rear wall flaps extending from their rear edges and front wall flaps extending from their front edges, the said rear wall flaps having disengageable interlocking parts, the front wall flaps being fixedly secured to the inner side of said front wall, the end walls being diagonally scored from their bottom front corners to their top rear corners to permit collapsing of the front and end walls upon the bottom with the rear wall flaps in overlapping relation to the rear wall.
- 30 5. A collapsible box formed of a blank scored for folding and comprising bottom, front and rear walls, and a cover disposed in alignment, the bottom having square end walls extending from the ends thereof, the end walls having square rear wall flaps extending from their rear edges and front wall flaps extending from their front edges, the rear wall flaps being detachably engageable and the front wall flaps being lapped upon and secured to the front wall, the end walls being diagonally scored to permit collapsing of the front and end walls upon the bottom with the rear wall flaps in overlapping relation to the rear wall and cover.
- 35 6. A collapsible box formed of a blank scored for folding and comprising bottom, front and rear walls, and a cover disposed in alignment, the cover being provided with collapsible front and end flanges, the bottom having square end walls extending from the ends thereof, the end walls having square rear wall flaps extending from their rear edges and front wall flaps extending from their front edges, the rear wall flaps being detachably engageable and the front wall flaps being lapped upon and secured to the front wall, the end walls being diagonally scored to permit collapsing of the front and end walls upon the bottom with the rear wall flaps in overlapping relation to the rear wall and cover.
- 40 7. In a collapsible lunch box, an integral blank of paper board cut and scored to provide a rectangular bottom panel the length of which is substantially twice its width, a rectangular front wall panel of the same size as said bottom panel and connected to the front edge thereof by a fold line, square end wall panels of half the size of said bottom panel and connected to the end edges thereof by fold lines, the end wall panels having diagonal fold lines and front flaps secured to said front wall panel so that the latter and the end wall panels are readily collapsible on the bottom panel, a rectangular rear wall panel of the same size as said bottom panel and connected to the rear edge thereof by a fold line,

bases of which are in line with the joint between the cover and the rear wall when the blank is in the flat, the front wall flaps being fixedly secured to the inner side of said front wall, the end walls being diagonally scored from their bottom front corners to their top rear corners to permit collapsing of the front and end walls upon the bottom with the rear wall flaps in overlapping relation to the rear wall, there being scores at the bases of the locking tongues of the rear wall flaps permitting their disposition in overlapping relation to the cover and the collapsing of the cover on the rear wall and the rear wall flaps superimposed thereon.

10 15 20 25 30 35 40 45 50 55 60 65 70 75

4. A collapsible box formed of an integral blank scored for folding and comprising a bottom, front and rear walls, and a cover disposed in alignment, the cover being joined to the upper edge of the rear wall, the bottom having substantially square end walls extending from the ends thereof, the end walls having rear wall flaps extending from their rear edges and front wall flaps extending from their front edges, the said rear wall flaps having disengageable interlocking parts, the front wall flaps being fixedly secured to the inner side of said front wall, the end walls being diagonally scored from their bottom front corners to their top rear corners to permit collapsing of the front and end walls upon the bottom with the rear wall flaps in overlapping relation to the rear wall.

5. A collapsible box formed of a blank scored for folding and comprising bottom, front and rear walls, and a cover disposed in alignment, the bottom having square end walls extending from the ends thereof, the end walls having square rear wall flaps extending from their rear edges and front wall flaps extending from their front edges, the rear wall flaps being detachably engageable and the front wall flaps being lapped upon and secured to the front wall, the end walls being diagonally scored to permit collapsing of the front and end walls upon the bottom with the rear wall flaps in overlapping relation to the rear wall and cover.

6. A collapsible box formed of a blank scored for folding and comprising bottom, front and rear walls, and a cover disposed in alignment, the cover being provided with collapsible front and end flanges, the bottom having square end walls extending from the ends thereof, the end walls having square rear wall flaps extending from their rear edges and front wall flaps extending from their front edges, the rear wall flaps being detachably engageable and the front wall flaps being lapped upon and secured to the front wall, the end walls being diagonally scored to permit collapsing of the front and end walls upon the bottom with the rear wall flaps in overlapping relation to the rear wall and cover.

7. In a collapsible lunch box, an integral blank of paper board cut and scored to provide a rectangular bottom panel the length of which is substantially twice its width, a rectangular front wall panel of the same size as said bottom panel and connected to the front edge thereof by a fold line, square end wall panels of half the size of said bottom panel and connected to the end edges thereof by fold lines, the end wall panels having diagonal fold lines and front flaps secured to said front wall panel so that the latter and the end wall panels are readily collapsible on the bottom panel, a rectangular rear wall panel of the same size as said bottom panel and connected to the rear edge thereof by a fold line,

substantially square rear wall flaps of substantially the same size as said end wall panels and connected to the rear edges thereof by fold lines, the rear wall flaps having tongues at their inner edges adapted to be interlocked when the box is erected, the tongues being connected to the rear wall flaps by fold lines in line with the upper edge of the rear wall panel when the blank is in the flat, and a rectangular cover panel of the same size as said bottom panel and connected to the upper edge of said rear wall panel by a hinge line, the cover panel having integral front and end wall flanges adapted to collapse on the inner side thereof when not in use, the arrangement being such that the box when erected for use is structurally rigid and resists inadvertent collapsing to a marked degree, the integral front and end wall flanges of the cover receiving the front and end walls of the box, and the rear wall flaps and rear wall panel providing in effect a rear wall of double thickness, the box being adapted to be collapsed for handy transportation when not in use by opening the cover, releasing the tongues, collapsing the front wall panel and end wall panels on the bottom panel with the rear wall flaps overlapping the rear wall panel and the tongues overlapping the cover panel, collapsing the front and end wall flanges of the cover thereon, folding the front wall panel inwardly over the bottom panel, folding the cover panel inwardly over the rear wall panel, and folding the rear wall panel and bottom panel outwardly in back-to-back relation, whereby a neat and compact flat package is formed which may be readily carried in the pocket of the user if desired.

HELEN M. HANSON.
